RAILWAY SIGNALING APPARATUS

Francis J. Ryan, Chicago, Ill.

Application August 16, 1934, Serial No. 740,071

10 Claims. (Cl. 246—223)

This invention relates to electrically operated semaphore signals used for the control of railway traffic, and more particularly to an improvement for economizing in the energy used for holding said signals in their different operated positions.

One apparatus or mechanism in common use for electrically operating semaphore signals with which I am familiar, comprises the well known Hall style-K electric motor signal. This style-K mechanism has an electro-magnetic clutch which is a part of the rotating system for moving the semaphore arm from the "stop" to the "caution" and the "proceed" positions, as well as for holding the semaphore arm in these positions. The clutch coil of the magnetic clutch, therefore, draws energy from the battery at all times except when the signal is at "stop" position. During the holding time the energy input to the clutch coil can be reduced about one-half without the signal kicking off. As the signals stand at clear a large percentage of the time, considerable energy is wasted in the clutch coil, because the Hall style-K mechanism does not provide any arrangement for reducing the current consumed by the clutch coil when the signal is at clear. Several schemes were developed involving the use of contacts on the mechanical circuit breaker in an effort to reduce this waste of current consumption, but these schemes were not satisfactory because it was impossible to bridge the period of transition from the rotating function to the holding function of the clutch. As a result the signal would "pump" and it was, therefore, found necessary to provide a time interval to bridge the gap. In the present invention a slow-releasing relay is utilized to bridge the gap. The relay is energized in multiple with the signal motor and closes contacts for short circuiting a resistance normally included in the holding circuit for the clutch coil so that full voltage is applied to the clutch coil when the motor is operating. When the motor cuts out the relay releases slowly removing the short from around the resistance a short interval thereafter, thereby including the resistance in the holding circuit of the clutch coil. The inclusion of the resistance in the holding circuit of the clutch coil reduces current consumption to approximately fifty percent.

The principal object of this invention is to devise an improved construction and arrangement of parts and circuits, in a semaphore signal operating mechanism, so as to reduce the energy consumption of the electromagnetic clutch, there-

by reducing the cost of operating the signaling system.

Further objects and advantages will appear as the description of the invention progresses and the novel features of the invention will be particularly pointed out in the appended claims.

Referring now to the drawings, Fig. 1 is a diagrammatic view which shows the mechanism and electrical connections of a device constituting one embodiment of the invention, said mechanism being illustrated more with a view of making their functions and operations clearly understood than with regard to their exact construction.

Fig. 1A is a diagrammatic representation showing when the contacts of the circuit controller are operated during the movement of the semaphore arm from its horizontal or zero degree position to its vertical or ninety degree position.

Fig. 2 is a circuit diagram illustrating the use of the invention applied to a Hall style-K two arm signal location on a single track territory.

Referring to Fig. 1, the invention is shown as applied to a well-known type of semaphore signal operating mechanism, such as manufactured by the Hall Switch and Signal Company, style-K electric motor signal and described in sec. #33 of the Hall Switch and Signal Company catalog of 1911. This type of semaphore signal operating mechanism comprises a semaphore arm 10 pivotally connected by the semaphore rod 11 to the semaphore segment 12. The semaphore segment 12 is pivoted at 13 and has teeth 14 near the lower outer edge which mesh with a pinion gear 15. The pinion gear 15 is secured to shaft 16 upon which is mounted the gear wheel 17. The shaft 16 is rotated in suitable bearings in the frame of the mechanism. Gear wheel 17 meshes with gear 18 which is secured to shaft 19. A governor 20 is also attached to shaft 19 to govern the speed of rotation thereof. An electro-magnetic clutch 21, comprising the clutch coil or winding, has its terminals connected to conducting rings 22 and 24 which are constantly in engagement with wipers 23 and 25. The clutch rotates with shaft 19. A clutch face plate 26 and gear wheel 27 are fastened to shaft 28 by any suitable means and rotate therewith. The clutch face plate 26 and clutch 21 rotate together only when the clutch coil is energized and the motor 31 is operating. Electro-magnetic clutches of this type are old and well known and need not, therefore, be more fully described. The gear wheel 27 meshes with gear 29 on shaft 30 which is rotated by motor 31. Attached to the semaphore segment 12 is an arm 32 pivotally con-

nected to arm 33 which is connected to shaft 34 for rotating the same when the semaphore segment 12 is rotated, either by the operation of motor 31 or by the restoration of the semaphore arm 10. Mounted on the shaft 34 are the semaphore circuit controlling cams 35, 36 and 37 for controlling the opening and closing of the semaphore circuit controlling contacts 81 to 85, inclusive, in accordance with the occupied position of the semaphore arm 10. As shown, the semaphore blade or arm 10 is at clear or its 90° position while the cams 35, 36 and 37 are shown in corresponding positions. TR represents the usual and well known track or home relay which is normally energized until a train enters the block section corresponding thereto. DR represents the distant relay which is jointly controlled by the distant and home track relays. Relay 50 is the well known slow-releasing relay commonly used in telephone systems. The battery B furnishes current for operating the relay 50, motor 31, and electromagnetic clutch 21 and has one of its terminals commoned to all the other batteries located at the other semaphore signaling positions in the system.

In the two arm system in Fig. 2, two mechanisms similar to the mechanism illustrated in Fig. 1 are shown diagrammatically by the motors 131 and 231, corresponding to motor 31; the electro-magnetic clutches 121 and 221, corresponding to the clutch 21; and the semaphore circuit controlling cams 135, 136 and 236. The cams 135 and 136 and the upper semaphore arm being operated by the motor 131 for the home track conditions, while the cam 236 and the lower semaphore arm is operated by motor 231 for the distant track conditions. In a two arm system of this type, it being well known that the upper semaphore arm indicates the home track condition while the lower semaphore arm indicates the distant track condition. A track relay TR' and a distant relay DR', are provided for controlling this two arm semaphore signal. A double-wound slow-releasing relay 150 somewhat similar to relay 50 is also shown. The system shown in Fig. 2 is used for a two arm system wherein each arm has two positions, the horizontal arm position being the stop position, while the lower arm position indicates the clear position. With the upper arm in clear position and the lower arm in stop position the signal therefore indicates "caution" which is the equivalent of the 45° position of the semaphore arm in Fig. 1.

Having briefly described the apparatus and system a detailed description of the circuit operations will now be given. For this purpose and referring to Fig. 1, it will be assumed that a train enters the block controlling track relay TR with the result that relay TR deenergizes and opens the holding circuit to the clutch coil 21 at armature contacts 63. The holding circuit for the clutch 21 when the semaphore arm is in clear or 90° position may be traced as follows: from positive terminal of battery B, contacts 63, clutch wiper 25, clutch ring 24, through the clutch coil winding 21, clutch ring 22, clutch wiper 23, resistance 52, circuit controller contacts 81 and 83 closed in 50 to 90°, contacts 71, contacts 61 to negative terminal of battery B. Due to the resistance 52 in this circuit the current consumed for holding clutch 21 energized is approximately one-half that formerly used for maintaining the clutch 21 energized. By the deenergization of the clutch 21, the clutch and shaft 18 are free to rotate independently of shaft 28 and motor 31.

It being well known in this type of apparatus previously described that as long as the clutch is held energized the semaphore arm is held in its operated position because the biased semaphore arm is unable to rotate shafts 28 and 30 and motor 31. However, when the clutch is deenergized the magnetic coupling between shaft 28 and shaft 18 is opened with the result that shaft 18 may now rotate independently of shaft 28. The construction of the semaphore arm 10 is such that when clutch 21 is deenergized the arm 10 falls to its horizontal or zero degree position. Arm 10 in falling from its 90° position to its zero position operates segment 12 on its pivot 13 by means of the rod 11. The teeth 14 on segment 15 being in mesh with pinion 15 causes the shaft 16 and gear wheel 17 to rotate thereby rotating shaft 18, governor 20 and clutch 21 by means of the gear 18 in mesh with gear wheel 17. The cams 35, 36 and 37 are also rotated from their 90° position to their 0° position by means of shaft 34, rods 33 and 32 which are pivotally connected to the segment 12 as shown. The deenergization of track relay TR also disconnects at contacts 62 the negative battery terminal of battery B from conductor 7 extending to the rear block section relay DR (not shown) to prevent the energization of such relay until the home track relay TR again energizes when the train passes unto the next or distant block section. At contacts 64, relay TR opens the circuit to the home DR relay which accordingly deenergizes and opens its contacts 71.

From the foregoing it will be seen that as a result of a train entering the block controlled by the semaphore arm 10 track relay TR and relay DR have deenergized, the clutch 21 is deenergized by the deenergization of relay TR and the semaphore arm 10 and cams 35, 36 and 37 are moved from their 90° positions to their zero degree positions.

In zero degree position cam springs 81 and 82 and cam springs 84 are closed by cams 35 and 36. As soon as the train leaves the home block section track relay TR again energizes and completes circuits for energizing motor 31 and relay 50 in multiple and for energizing clutch 21. The circuit for energizing motor 31 and relay 50 in multiple may be traced as follows: from positive terminal of battery B, contacts 63, through the motor 31 and relay 50 in multiple, cam contacts 84, contacts 61 to negative pole of battery B. Relay 50 energizes and at armature 51 closes a shunt around resistance 52 so that the clutch 21 receives full battery potential during motor operations. The circuit for energizing clutch 21 may be traced as follows: from positive terminal of battery B, contacts 63, clutch wiper 25, clutch ring 24, through the clutch coil 21, clutch ring 22, clutch wiper 23, armature 51, cam spring 81 and 82 now closed by cam 35, contacts 61 to the negative terminal of battery B. Due to the energization of clutch 21 the motor 31 is magnetically coupled to the semaphore arm 10 in the manner previously described with the result that the arm and cams are rotated from zero degree position. When cam 37 is rotated to its 43° position cam springs 85 close to prepare a circuit for motor 31 which is only closed when the train leaves the next or distant block. When cam 36 is rotated past its 44° position cam springs 84 open the motor and relay circuit to stop the motor. The momentum of the motor and apparatus stops the arm 10 and cams in their 45° position. Relay 50 deenergizes after an interval and at armature 51 removes the shunt from around resistance 52 to reduce the current flow in 75

the holding circuit to the clutch 21. The holding circuit at this time being the same as that traced for originally energizing the clutch 21 with the exception that the resistance 52 is now included in this circuit.

- 5 The semaphore arm 10 and cams 35, 36 and 37 stay in their 45° positions until the train leaves the distant block section, thereby causing the distant track relay to energize and complete the 10 circuit for energizing relay DR as follows: from the positive terminal of the distant battery corresponding to battery B, over common conductor 8, contacts 64, winding of relay DR, conductor 7', and through contacts corresponding to contacts 15 62 on the distant track relay to the negative pole of the distant battery. Relay DR, upon energizing, at contacts 71 completes a circuit for energizing the motor 31 and relay 50 in multiple as follows: from the positive terminals of battery B, contacts 63, through the windings of the motor 31 and relay 50 in multiple, cam springs 85 now closed by cam 37, contacts 71, contacts 61 to the negative pole of battery B. In the same manner 20 as previously described relay 50 at armature 51 again shunts the resistance 52 to increase the current flow in clutch 21 and the semaphore arm 10 and cams 35, 36 and 37 are moved from their 25 45° positions toward their 90° positions. In 50° position cam 35 opens cam springs 81 and 82 and 30 closes cam springs 81 and 83 thereby completing the following circuit for clutch 21: from positive pole of battery B, contacts 63, wiper 25, ring 24, coil 21, ring 22, wiper 23, armature 51, cam springs 81 and 83, contact 71, contact 61, to negative pole 35 of battery B. When the semaphore arm 10 and cam 37 reach their 89° position the cam springs 85 opens the circuit to motor 31 and relay 50 to stop the motor and deenergize relay 50. The 40 momentum of the motor, however, operates the semaphore arm 10 and cams to their 90° on clear position. When relay 50 deenergizes after an interval said relay at armature 51 again includes the resistance 52 in the last traced circuit for clutch 21 to complete the holding circuit. The holding 45 circuit for maintaining clutch 21 energized includes the resistance 52 to reduce the battery consumption and the semaphore arm is held in its 90° or clear position until such time as a train enters this section.
- 50 The invention as applied to a so-called "Two-arm system" is shown in Fig. 2 wherein the upper semaphore arm indicates home track conditions of the home block section, while the lower arm indicates the distant track conditions of the distant block section. In this system each semaphore arm has only two positions, the horizontal or zero degree position being the stop position while the downward slanting position or the 60° position being the clear position. A separate operating mechanism, similar to that disclosed in Fig. 1, is provided for each semaphore arm and the different mechanisms and parts in Fig. 2 corresponding to similar parts in Fig. 1 have reference characters only differing in the hundreds digits while the tens and units digits of the reference characters are the same for similar parts. In Fig. 2 the semaphore arms 110 and 210 and the cams 135, 136 and 236 are shown in their 60° or clear position. In this position the holding circuit for clutch 121 may be traced as follows: from positive pole of battery B', contacts 163, through the wipers, conducting rings and winding of clutch 121, resistance 152, contacts 161 to the negative pole of battery B'. The holding circuit for clutch 221 may be traced as follows:

from positive pole of battery B', contacts 163, through the wipers, conducting rings and winding of clutch 221, resistance 252, cam springs 134 now closed, contacts 171, contacts 161 to the negative pole of battery B'. Since the clutches 121 and 221 are maintained energized over their holding circuits the semaphore arms 110 and 210, respectively, are maintained in their clear positions.

When a train enters the home block section 10 the home track relay TR' associated therewith deenergizes and opens the holding circuits to both clutches 121 and 221 at contacts 161 and 163. In response to the deenergization of clutch 121 the upper semaphore arm 110 and cams 135 15 and 136 rotate to their zero degree positions and in response to the deenergization of clutch 221 the lower semaphore arm 210 and cam 236 rotate to their zero degree positions. At contacts 162 relay TR' opens the circuit to the DR relay associated with the block section to the rear and at contacts 164 opens the circuit to DR' relay which accordingly deenergizes.

When the train leaves the home block section and enters the distant block section, track relay 25 TR' again energizes to complete circuits for operating the upper semaphore arm 110 to its 60° or clear position as follows: from positive pole of battery B', contacts 163 through the motor 131 and upper winding of relay 150 in multiple, cam 30 springs 137 closed by cam 136 from 0° to 59°, contacts 161 to the negative pole of battery B'. Relay 150, upon energizing over the above-traced circuit, at armature 151 shunts the resistance 152 to increase current flow in the clutch circuit 35 which may be traced as follows: from the positive pole of battery B', contacts 163, through the wipers, conducting rings and winding of clutch 121, armature 151, contacts 161 to the negative pole of battery B'. Due to the energization of 40 the clutch 121 the semaphore arm 110 is coupled to the motor 131 with the result that the motor now moves arm 110 and cams 135 and 136 from zero degree position toward their 60° position. When cam 136 is rotated to its 59° position cam 45 137 open the circuit to the relay 150 and motor 131 which deenergize. Due to the momentum of the motor and mechanism, the arm 110 and cams 135 and 136 are, however, rotated to the 60° or clear position. Relay 150, upon deenergizing, at armature 151 removes the shunt from 50 around resistance 152 with the result that the previously traced circuit for clutch 121 now includes resistance 152 instead of contacts 151 for holding the arm 110 in its clear position. Cam 55 135 in position 59° to 60° closes cam springs 134 to prepare the circuits for operating and holding the lower semaphore arm 210.

When the train leaves the distant block section the track relay associated therewith completes 60 the circuit for energizing relay DR' over armature 164, common conductor 108 and battery at the distant section. At contacts 171 relay DR' completes the motor and relay circuit and the clutch circuit. The motor and relay circuit may be 65 traced as follows: from positive pole of battery B', contacts 163, through the motor 231 and lower winding of relay 150 in multiple, cam springs 237 closed by cam 236 from 0° to 59°, cam springs 134 now closed by cam 135 in its 60° position, contacts 70 171, contacts 161 to the negative pole of battery B'. The motor 231 and relay 150 operate and relay 150 operates its armatures 151 and 251 to short resistances 152 and 252, respectively. The clutch 221 is now energized over the following 75

circuit: from the positive pole of battery B', contact 163, through the wipers, conducting rings and winding of clutch 221, armature 251, closed cam springs 134, contacts 171 and 161 to the negative pole of battery B'. Armature 151 shorts resistance 152 to momentarily increase the current flow through clutch 121. Due to the operation of motor 231 and the energization of clutch 221 the arm 210 and motor 231 are magnetically coupled so that the motor now moves arm 210 and cam 236 from its zero position toward its 60° position. When cam 236 reaches its 59° position, cam springs 237 open the circuit to the motor 231 and relay 150 to deenergize the same. The momentum of the motor and mechanism, however, rotates the arm 210 and cam 236 to its 60° positions. After a short interval, slow to release relay 150 deenergizes and removes the short circuits from around resistances 152 and 252 at armatures 151 and 251. The resistances 152 and 252 are now included in the holding circuits of clutches 121 and 221, respectively, instead of armatures 151 and 251 to decrease the current consumption during the time the semaphore arms 110 and 210 are held in their clear positions by the continued energizations of the clutches 121 and 221.

Having described the invention, what is considered new and is desired to be protected by Letters Patent is set forth in the following claims.

What is claimed is:

1. In combination, a semaphore biased to stop position, a motor, an electromagnetic clutch for coupling said motor and semaphore, means for operating said motor and for energizing said clutch to move said semaphore to an operated position, a holding circuit including a resistance to reduce the current flow therein for maintaining said clutch energized to hold said semaphore in its operated position, a relay operated with said motor, and contacts operated by said relay for shunting said resistance to increase the current flow in said clutch thereby increasing the magnetic pull of said clutch during motor operations.

2. In combination, a semaphore arm, a motor, an electromagnetic clutch for coupling said motor to said arm when said clutch is energized, a switch arranged to be operated when said arm is moved, a circuit for operating said motor and a circuit for energizing said clutch controlled by said switch, a holding circuit including said switch for maintaining said clutch energized, a resistance included in said holding circuit to reduce current flow therein, a relay controlled by said switch for shunting said resistance to increase the magnetic pull of said clutch during the operating time of said motor, and track controlled means for supplying operating current to said circuits and relay.

3. In combination, a semaphore arm, a motor, an electro-magnetic clutch for coupling said motor to said arm when said clutch is energized, a switch arranged to be operated when said arm is moved, a holding circuit for maintaining said clutch energized including a resistance to reduce current flow therein, track controlled means for supplying operating current through said switch to operate said motor and clutch, a relay controlled by said switch and operated in multiple with said motor, and contacts operated by said relay for shunting said resistance to strengthen the magnetic pull of said clutch during motor operations.

4. In combination, a semaphore arm, a motor,

an electromagnetic clutch for coupling said motor to said arm when said clutch is energized to operatively move said arm in response to motor operations and to hold said arm in its set positions after motor operations, a holding circuit including a resistance to reduce current flow therein normally maintaining said clutch energized, track controlled means operated for connecting and disconnecting operating current to and from said motor and said holding circuit, the disconnection of operating current from said holding circuit in response to the operation of said track controlled means deenergizing said clutch to uncouple said motor and arm to move said arm from one position to another, the reoperation of said track controlled means reconnecting operating current to said motor and holding circuit to move said arm from said other position, a relay operated in multiple with said motor, and contacts on said relay for shunting said resistance in said holding circuit to increase the current flow through said clutch during motor operations.

5. In combination, a semaphore arm having first, second, and third positions, a motor, an electro-magnetic clutch for coupling said motor to said arm when said clutch is energized to operate said arm in response to motor operations and to hold said arm in its set positions after motor operations, a switch having three positions corresponding to the three positions of said arm and arranged to be operated when said arm is moved, a holding circuit including a resistance to reduce current flow therein normally maintaining said clutch energized, home track controlled means operated for connecting and disconnecting operating current to and from said motor and clutch, the disconnection of current from said holding circuit deenergizing said clutch to uncouple said arm and motor, said arm moving from first position to third position in response to the deenergization of said clutch, circuit controllers closed in third position of said switch for operating said motor and clutch to move said arm and switch to second position in response to the reconnection of operating current by said home track controlled means, said circuit controllers for said motor operated at second position of said switch to stop said arm in second position and to maintain said holding circuit closed, other circuit controllers closed in second position of said switch, distant track controlled means for connecting operating current through said other circuit controllers for operating said motor and clutch to move said arm and switch to first position, said other circuit controllers operated in response to said switch reaching first position for stopping said arm in first position and for maintaining said holding circuit closed, a relay operated each time said motor is operated, and contacts operated by said relay for shunting said resistance in the holding circuit to increase current flow through said clutch during each motor operation.

6. In combination, a semaphore signal comprising two arms, a motor for each arm, an electromagnetic clutch for each arm for coupling its corresponding arm to its corresponding motor, means including track controlled means for operating the first motor and for energizing the first clutch to move the first semaphore arm to an operated position, a first holding circuit including a resistance to reduce current flow therein for maintaining said first clutch energized to hold said first arm in its operated position, means including additional track controlled means for op-

erating the second motor and for energizing the second clutch to move the second semaphore arm to an operated position, a second holding circuit including a resistance to reduce current flow 5 therein for maintaining said second clutch energized to hold said second arm in its operated position, a relay operated with either one of said motors, and contacts on said relay for shunting both said resistances to increase the current flow 10 in both said clutches thereby increasing the magnetic pull of said clutches during motor operations.

7. In combination, a semaphore arm, a motor adapted to move said arm, holding means for holding said arm in operated position, a holding circuit including a resistance to reduce current flow therein for maintaining said holding means energized, a relay, means for simultaneously operating said motor and relay, and contacts 15 operated by said relay for shunting said resistance to increase the current flow in said holding means during motor operations.

8. In combination, a semaphore arm, a motor, an electromagnetic clutch, a circuit for maintaining said clutch energized, means for closing said clutch circuit, the energization of said clutch magnetically coupling said semaphore arm and said motor, a circuit for said motor, a relay connected in said circuit in multiple with said motor, 20 means for closing said multiple circuit to simultaneously operate said motor and said relay, the operation of said motor moving said arm from one position to another by means of said magnetic coupling, a resistance included in said clutch circuit, and contacts operated each time said relay is operated for shunting said resistance to increase current flow in said clutch circuit thereby increasing the strength of the magnetic coupling between the semaphore arm and motor during 25 each motor operation.

9. In combination, a semaphore arm having a plurality of operated positions, a motor, an elec-

tromagnetic clutch, a circuit for operating said motor, a relay connected in said circuit in multiple with said motor, a circuit for said clutch, means for closing all said circuits simultaneously to operate said motor and relay and to energize 5 said clutch, the energization of said clutch magnetically coupling said semaphore arm and motor and the operation of said motor thereafter moving said semaphore arm, means for opening said motor and relay circuit in response to said 10 arm reaching a predetermined position to stop the motor and arm, means for reclosing said multiple motor and relay circuit to reoperate said motor and relay to cause said motor to move said arm to another position, means for maintaining 15 said clutch circuit closed to maintain said arm in its operated positions, a resistance included in said clutch circuit, and contacts operated each time said relay is operated for shunting said resistance to increase the current flow in said clutch 20 thereby increasing the strength of the magnetic coupling between the semaphore arm and motor during each motor operation.

10. In combination a semaphore arm having a plurality of operated positions, a motor, an 25 electromagnetic clutch, a circuit for operating said motor, a relay connected in said circuit in multiple with said motor, a circuit for said clutch, means for closing all said circuits simultaneously to operate said motor and relay and to energize 30 said clutch, the energization of said clutch magnetically coupling said semaphore arm and motor and the operation of said motor thereafter moving said semaphore arm, a resistance included in said clutch circuit, and contacts operated each 35 time said relay is operated for shunting said resistance to increase the current flow in said clutch thereby increasing the strength of the magnetic coupling between the semaphore arm and motor during each motor operation. 40

FRANCIS J. RYAN.
